TOILET BOWL DEODORIZER

Richard E. Goodman, 1053 Roscomare,
Los Angeles, Calif. 90024

Filed Nov. 15, 1967, Ser. No. 9,420

Term of patent 14 years

(Cl. D23—150)

FIG. 1 is a perspective view of a toilet bowl deodorizer, showing my new design, the fragmentary toilet bowl is shown in broken lines for illustrative purposes only;

FIG. 2 is a top plan view thereof;

FIG. 3 is a right side elevational view;

FIG. 4 is a front elevation thereof;

FIG. 5 is a left side elevational view;

FIG. 6 is a bottom plan view taken in the direction of line 6—6 in FIG. 3;

FIG. 7 is a rear elevational taken in the direction of line 7—7 in FIG. 5;

FIG. 8 is a top plan view of a modified embodiment of the toilet bowl deodorizer shown in FIG. 1;

FIG. 9 is a left side elevation thereof;

FIG. 10 is a front elevation thereof; and

FIG. 11 is a right side elevation thereof.

I claim:

The ornamental design for a toilet bowl deodorizer, substantially designed as shown and described.
